UNITED STATES PATENT OFFICE

2,330,530

PAPER LAMINATING MACHINE

John N. Tuttle, Philadelphia, Pa., assignor to The
Glassine Paper Company, West Conshohocken,
Pa., a corporation of Delaware

Application August 12, 1939, Serial No. 289,740

10 Claims. (Cl. 154—37)

This invention relates to a paper laminating machine, and has particular reference to a machine adapted to control sheets of paper to a high degree of precision so as to produce satisfactory high grade products even when laminating materials normally difficult to handle.

In the patents to Beecher 1,936,375, Nelson 1,965,719 and Connor 2,128,739, there are described methods and apparatus for the laminating of glassine paper by the use of wax or resinous materials. Such laminated products are useful particularly in the packaging of foodstuffs, in which case the glassine not only contributes its property of grease resistance, but also serves to provide an attractive package of transparent or semi-transparent nature through which the contents may be viewed. Such a transparent package must make an attractive appearance, and consequently, the laminated glassine used for its construction must not only be without flaws initially, but it must also stand up under conditions of exposure and use without separation of its constituent plies. Various other uses of laminated glassine, for example, in the making of lampshades, require it to be substantially without flaws.

The production of substantially perfect glassine requires careful control of numerous factors entering into its formation, for example, the careful control of the amount of adhesive material applied to the glassine sheets, of the speeds of feed, and the tensions on the sheets, and of the handling of the heated laminated product through the cooling stages. Unless such careful handling occurs throughout the manufacture, separation of the plies may occur with the appearance of bubbles, either initially or by setting up of differential stresses upon standing or handling of the product made up of sheets which were treated differently during the laminating process.

It is a general object of the present invention to provide a machine adapted for close control of all of the factors which enter into the production of a product such as laminated glassine. It will be evident that the improved machine may be used for the laminating or mere coating of other types of papers; but throughout the following description, the lamination of glassine will be particularly stressed because, by reason of its transparency, flaws in the finished product are particularly noticeable and must be avoided. The machine is also adapted for the lamination of sheets such as those composed of Cellophane. Different types of sheets may be laminated to

each other, for example, glassine or Cellophane to heavier papers.

The various subsidiary objects of the invention relate to the provision of fine adjustments to secure equal or properly related tensions of various sheets which are being laminated; the adjustment of such sheets to insure uniform stresses to avoid subsequent breaking apart of the plies, or curling; the control of the adhesive supplied to the sheets, not only from a mechanical standpoint, but also from the standpoint of temperature and resulting viscosity; and the provision for fine adjustment of pressures upon the sheets in the region where they are secured together.

The above and other objects of the invention, particularly relating to details of construction and detailed features of control, will become apparent from the following description, read in conjunction with the accompanying drawings, in which:

Figure 1 is a diagrammatic elevation showing particularly the various actions of parts of the machine on component papers of a laminated product;

Figure 2 is an elevation of the major portion of the machine with some parts broken away to show details;

Figure 3 is a sectional elevation showing means for controlling the take-up of a finished laminated product;

Figure 4 is a plan view of a heating and recirculating arrangement for adhesive or coating material;

Figure 5 is a sectional elevation of the same;

Figure 6 is a sectional elevation showing particularly the laminating rollers and associated devices;

Figure 7 is a sectional plan view of the same;

Figure 8 is a transverse section showing particularly a scraping device associated with a guiding roller;

Figure 9 is a fragmentary elevation illustrating means for adjusting certain guiding rollers;

Figure 10 is a vertical section of the same matter;

Figure 11 is a horizontal section taken on the plane indicated at 11—11 of Figure 9;

Figure 12 is a sectional elevation showing particularly the means for controlling a roll of paper which supplies the machine;

Figure 13 is a horizontal section showing a bearing mounting therefor;

Figure 14 is a vertical section taken on the plane indicated at 14—14 of Figure 12;

Figure 14A is a vertical section taken on the plane indicated at 14A—14A of Figure 12;

Figure 15 is a sectional fragmentary elevation showing particularly means for controlling the distribution and application of adhesive to a sheet of paper;

Figure 16 is a fragmentary plan view showing particularly the means for controlling the application of adhesive to the edges of a sheet; and

Figure 17 is a fragmentary plan view showing the means for mounting and heating an equalizer.

Referring first to Figure 1, there will be clear from consideration of this figure the fashion in which sheets to be laminated are handled and the nature of the adjustments which are provided in the machine, the directions in which various supply rolls and handling rollers may be adjusted being indicated by arrows.

On shafts 2, 4, 6 and 8 are mounted supply rolls of paper indicated at 10, 12, 14 and 16, respectively. As illustrated, all four of these sheets have adhesive applied to them and the product is a four-ply laminated material. An additional ply (indicated in chain lines in Figure 1) may be inserted between the two inner plies without the application of adhesive thereto, since it will contact with adhesive coated surfaces of the two inner plies. If such a fifth ply is fed, a five-ply paper will result.

Adhesive is applied to the various sheets illustrated by rollers 18, 20, 22 and 24, respectively, which run in baths of adhesive contained in tanks 26, 28, 30 and 32. The sheet 10 passes to its adhesive applying roller 18 after passing over controlling and smoothing rollers 34 and 36, the latter of which rollers may be abrasive and driven opposite the direction of movement of the sheet to roughen the surface and thereby promote adhesion. After contacting with the roller 18, it engages the equalizer rod 38, whence it passes beneath a controlling roller 40 between the laminating rollers 42 and 44. At this point it meets the other sheets and passes with them between the roller 42 and roller 46. The roller 42 has a metallic surface, while the rollers 44 and 46 are desirably rubber faced.

In similar fashion, the sheet 12 passes about the guiding rollers 48 and 50, then in contact with its adhesive applying roller 20 and thence over the equalizer 52 and beneath the controlling roller 54.

Sheet 14 likewise passes about the rollers 56 and 58, its adhesive applying roller 22, its equalizer 60 and its controlling roller 62. Similar rollers 64 and 66, equalizer 68 and roller 70 control the passage and condition of the fourth sheet 16.

The laminated product 72 passing from the rollers 42, 44 and 46 extends about the chilling drums 74 and 76 and is wound upon a reel indicated at 80 on the shaft 78.

The take-up action of the reel 80 is effected by the means indicated in Figure 3. A shaft 82, which is positively driven, as indicated hereafter, is provided with a pulley driving a belt 84, which extends about a pulley 86 on the shaft 78. A take-up roller 88 engaging the belt 84 is carried by a bell crank 90, the position of which may be adjusted by a screw and nut arrangement indicated at 92. The shaft 78 would be driven, if the belt did not slip, at a speed such that the periphery of the wheel would be moving faster than the supply of laminated material, even when the reel had a minimum diameter. Proper slippage and a desired tension upon the laminated product are secured by adjustment of roller 88.

By this means a quite accurate adjustment of the pull on the laminated product may be secured.

The shaft 82 carries a pinion 94 meshing with a gear 96 which in turn is connected with a pinion 98 driving the meshing gears 100 and 102 secured to the shafts of the chilling drums 74 and 76. Thus these drums are driven at predetermined speed during the cooling of the laminated product, as is necessary for satisfactory results, particularly in the handling of thin papers to avoid tendency toward curling. The drums 74 and 76 may be cooled by water circulation if necessary.

While the machine is well adapted for the application of adhesive at room temperature, in general, particularly in the laminating of glassine, it is desirable to apply adhesive at an elevated temperature. For example, the adhesive may be a wax or other thermoplastic material, or may be a material such as a resin or rubber composition in solution in a volatile solvent, which is desirably applied in heated condition so that rapid evaporation of the solvent will take place, and accordingly so that laminating may be accomplished quite rapidly. For this reason, there is supplied an adhesive tank 104 jacketed as indicated at 106 so that its contents may be heated by steam or other medium passing through the jacket by way of the openings 108 and 110. A valve controlled drain indicated at 112 may be provided for the tank. Within the tank there is located a pump 114 which may be of centrifugal type driven by a motor 116. The pump 114 is arranged to deliver the adhesive to the various tanks 26, 28, 30 and 32 through pipe connections indicated at 118. In order to control the delivery and also provide recirculation within the tank, there is a bypass connection 120 adapted to bypass some of the liquid delivered by the pump through a valve indicated at 122. By adjustment of this valve, a desired proportion of the liquid may be recirculated within the tank 104, to effect a stirring action, the remainder of the liquid being delivered to the adhesive applying tanks. New makeup material may be delivered to the tank 104 from time to time, as may be required. By reason of the provision for recirculation, admixture may be effected directly within the tank 104 in some cases.

Referring to Figure 2, it will be noted that the various tanks 26, 28, 30 and 32 are provided with return overflow connections indicated at 124 communicating with the supply tank 104. The feed to the various adhesive tanks is in excess of the requirements, and consequently continuous overflow takes place, so that recirculation is effected to maintain uniformity of temperature and composition of the adhesive material as it is applied to the paper. The various tanks 26, 28, 30 and 32 are preferably jacketed as indicated at 126 so as to be heated to a proper temperature by a suitable medium, such as steam. Preferably, the heating medium to these tanks, as well as to the tank 104, is thermostatically controlled, since for best results a given amount of adhesive must be applied to the paper within a relatively narrow range of temperature. If small tanks 26, 28, 30 and 32 are used they may be heated only in starting up the apparatus.

Front and rear brackets 128 and 130 are provided to support the supply rolls of paper and the details of the mountings of these rolls are specifically illustrated in Figures 12 to 14A, inclusive, in which there are detailed the elements corresponding to the roll 10.

The shaft 2 which carries this roll is mounted

in front and rear bearing members carried by the front and rear brackets 128 and 130, respectively. The rear bearing comprises a sliding block 132 mounted on the bracket 130 for sliding movements transverse to the direction of the shaft 2. This block is located in adjusted position by means of a screw 134 mounted in the bracket and threaded into the block.

On the front bracket 128 there is secured a member providing arcuate tracks, indicated at 137, receivable within arcuate grooves 139 provided in a bearing block 138. This bearing block is adapted by this arrangement to have a rotary movement about the axis of a fixed pin 136 extending into a cylindrical opening in the block 138. The shaft 2 is held by an upper bearing member 142 secured in position to embrace the shaft by a thumb screw 140. By reason of these arrangements it will be evident that the rear end of the shaft may be adjusted transversely, while the forward bearing will permit such transverse movement to take place without binding of the shaft in its bearings and about the pin 136 as a pivot.

At its forward end the shaft 2 is provided with a grooved disc 144 about which the elements 146 of a brake may be adjustably clamped by means of a screw arrangement indicated at 147. Thus adjustable friction may be applied to the disc 144 to retard free movement of the shaft 2 to a predetermined degree. The brake members 146 are engaged between collars on a screw 150 which threads into an extension 148 of the front bearing 132. The screw 150 is provided with a hand wheel 152 so that it may be threaded into or out of the extension 148. Thus the brake is moved axially and by its movement the shaft 2 is moved axially. The brake, therefore, not only serves to effect control of the tension on the paper, but also effects axial control and adjustment of the shaft.

Rolls of paper 10 are secured on the shaft 2 by means of the conventional split cones indicated at 154, secured to the shaft by set screws.

The preliminary controlling rollers, such as 34 and 36, are adjustable in pairs and their mountings and adjustments will be apparent from Figures 9, 10 and 11, which show particularly the elements associated with rollers 34 and 36 which handle sheet 10. These rollers are mounted by means of roller bearings indicated at 156 upon rods 158, which are carried at the front and back of the machine by vertically adjustable slides 160. These slides are provided with teeth 162 to form racks engageable by pinions 164, which are secured to a shaft 166 provided at its forward end with a hand wheel 168. By manipulation of any one of the four hand wheels 168 vertical adjustments of the pair of rollers may be provided, the adjustments being maintained by suitable ratchet arrangements 169. By their adjustment, arcuate control of the direction of feed of the corresponding sheets to the adhesive applying rollers may be obtained.

The rollers corresponding to 36, i. e., 36, 50, 58 and 66, may be of abrasive nature so as to abrade the surface of a highly calendered paper to enable the adhesive to bind more securely the plies of the product. In such case, the roll may be driven opposite the direction of movement of the paper by any suitable means.

Mounted on the bearings of the shafts of the adhesive applying rollers for adjustment about the axis of these rollers are bracket members indicated at 170 in Figure 15, which, together with Figures 16 and 17, relates primarily to those

elements associated with the adhesive applying roller 18. The brackets 170 are provided in pairs at opposite ends of the rollers and each is slotted as indicated at 172 to receive a stud 174 extending from an equalizer supporting member 176. The upper end of the member 176 is recessed to receive a plate 178 between the end of which and another plate 180 set at an angle with respect thereto, as illustrated in Figure 15, there lies an equalizer rod 184 in position to be rotated by the paper. This equalizer rod 184 may be of the type illustrated in Moller Patent 1,853,569, dated April 12, 1932, and consists of a circular rod about which is wound a wire the convolutions of which are in contact with each other. As is well known in the art, by proper choice of the wire wound about the equalizer rod a very accurate control of the amount of adhesive material applied to the paper is provided. This rod 184 may be rotated merely by contact with the paper, or alternatively, it may be positively driven at a suitable rate of speed. Rotation, however, is not absolutely essential, though it is desirable to provide even wear of the wire wound on the rod and its longer life. Each of the equalizer rods heretofore mentioned, i. e., 38, 52, 60 and 68, has this same construction.

The end of the member 176 below the plate 180 is slotted, as indicated at 182, to provide passages for return of excess adhesive to the surface of the roller 18 and thence to the tank 26.

It is important that the equalizer rod be maintained at a proper temperature to function properly. Accordingly, the member 176 is provided with an inset heating tube 186 through which heating fluid, for example, steam or, desirably, oil, at properly controlled temperature, may be circulated. A single turn of such tube is found sufficient, particularly if the heating is effected through the means of circulating oil maintained at proper temperature. The lower end of the member 176 is preferably turned, as indicated, for the purpose of securing rigidity to avoid bowing of this member and its equalizer rod under the pressure of a paper web.

In order to avoid troublesome distribution of adhesive at the edges of the laminated product and flow of the adhesive over the surfaces of the laminated rollers, it is desirable to avoid to as great a degree as possible the application of adhesive at the margin of a sheet. For this purpose at each end of the adhesive applying roller 18 and underlapping the sheet fed thereto there is a blade 188 adjustably securable upon a fixed rod 190 by means of a clamping screw 192. This blade engages the adhesive applying roller 18, scraping therefrom the adhesive material and also lifting its edge of the sheet slightly above the adhesive applying roller to thereby prevent application of adhesive to the margin.

Referring now to Figures 6 and 7, there are illustrated therein the various means for adjusting the actual laminating pressure rollers 42, 44 and 46. Referring first to the rubber faced roller 44, it is journaled in bearing blocks 194 and 196 adapted to slide transversely on tracks 198 and 200, which extend on opposite sides of the roller 42 so that the rubber roller may be located on either side thereof. Threaded into extensions of these blocks 194 and 196 are screws 202 and 204. The screw 202 is driven through bevel gears 206 from the bored shaft 208 of a hand wheel 210. The screw 204 is in turn driven through bevel gears 212 by means of the shaft 214 passing through the shaft 208 and carrying

a crank 216 adapted to be rotated by means of a handle 218. The crank 216 may be clamped to the hand wheel 210 by means illustrated at 220. When this means is freed, however, the hand wheel and crank may be independently adjusted. Thus it will be evident that the two ends of the roller 44 may be independently adjusted with respect to the roller 42, while, when the crank and hand wheel are clamped together the roller 44 may be moved bodily relative to the roller 42. Thus a fine control of the pressure between these rollers may be secured and may be varied along the length thereof.

The roller 46 is similarly adjustable for vertical movement. It is mounted in the bearing blocks 222 and 224 slidable on vertical track members 226 and 228. Adjustment of these bearing blocks is effected in the same fashion as adjustment of the bearing blocks 194 and 196 through the medium of the hand wheel 230 and crank wheel 232, which may be independently adjusted or simultaneously adjusted by clamping them together by the means indicated at 234.

The roller 40 which controls the sheet 10 is also adjustable both horizontally and vertically by the means illustrated in the lower portion of Figure 6. As shown therein, the roller is freely mounted on a rod extending between blocks 236 and 238 vertically adjustable in supporting members 244 and 246 by means of screws 240 and 242, respectively. The members 244 and 246 are in turn horizontally adjustable on tracks 248 and 250, to which they are clamped in fixed position by suitable screws.

In view of the minute holes which generally occur in papers, some adhesive may pass through the paper engaging the roller 40 and the corresponding rollers, and consequently each of these is provided with a scraping device in the nature of a blade 252 extending lengthwise of the roller and adjustably supported by means of a pair of arms indicated at 254, as illustrated in Figure 8. These blades serve to remove the small amounts of adhesive material which may pass through the paper.

Returning to Figure 2, there are illustrated therein the various driving devices for the parts of the machine. A pulley driven by a motor or other source of power is indicated at 256. This drives at suitable speed a cone pulley 258 about which and a cooperating cone pulley 262 secured to shaft 82 is trained a shiftable driving belt 260. Through suitable gearing there is driven the vertical shaft 264 which drives through a worm and wheel connection the steel roller 42, the rollers 44 and 46 being driven through the paper from this roller. By means of link belts there is also driven the adjustable speed device indicated at 266, the driven member of which is connected to the gear box 268 from which extend chain drives to the adhesive applying rollers 18, 20, 22 and 24. Thus the steel roller 42 is driven at a substantially constant speed while the adhesive applying rollers 18, 20, 22 and 24 are driven at variable speeds relatively to the paper pulled through the machine by the roller 42 to secure the desired application of adhesive. The speed of shaft 82 may also be varied with respect to the speed of roller 42 by shift of belt 260 on the cone pulleys 262 and 258.

If heated adhesives are used, for example, molten wax, it is essential for best results that certain of the rollers be heated to a proper temperature to maintain the adhesive in a uniform condition

throughout the operation. To this end rolls 18, 20, 22 and 24 and the steel roll 42 are heated with the same hot oil which is used to heat the equalizer rods. Connections for the circulation of the

5 hot oil may, in all cases, be along the lines indicated in connection with roller 42 in Figures 6 and 7. In the case of roller 42, there extends through its hollow shaft into the roller a tube 270, into which the heated oil is introduced. Return flow takes place about the tube into a box 272 surrounding one end of its shaft, and thence returns through the pipe 274 to the supply. The oil thus circulated through roller 42 and similarly through the adhesive applying rollers and 10 the equalizers may have its temperature thermostatically controlled to insure the proper application of the adhesive.

While there is illustrated in Figure 1 the arrangement of the machine for the lamination 20 of sheets such, for example, as glassine paper, the parts of the machine may be rearranged for the proper handling of other materials which are to be laminated and/or coated. Some materials, for example, such as cardboard, could not be given 25 a turn of small radius such as indicated in Figure 1, and if, for example, glassine or similar thin paper is to be laminated to cardboard, or the like, the roller 44 may be withdrawn from cooperation with roller 42 and may serve as a guide roller 30 to feed cardboard through the nip of rollers 42 and 46, the feed being so arranged that curvatures of small radii are avoided. It will be evident that the various adhesive applying arrangements may be associated in various combinations.

The various adjustments which are provided and which have been described are designed to insure uniform, flawless lamination, particularly in cases, such as the lamination of glassine, in 40 which flaws would be highly objectionable. By the adjustment of temperatures and speeds of rotation of the adhesive applying rollers, as well as by adjustment of the equalizer rods, such as 38, the amount of adhesive applied to the paper may 45 be readily controlled. Further, control is effected by the proper location of preliminary guiding rollers, such as 34 and 36, which determine the angle of approach of the paper to the adhesive applying roller. The pressure of the paper on the 50 equalizer and the arc of its contact therewith may be adjusted by the vertical adjustment of a roller such as 40, while horizontal adjustment of this roller determines the angle of approach of the sheet to the nip of rollers 42 and 44. The 55 adjustment of the shaft 2 and corresponding shafts carrying the supply rolls makes possible not only fine adjustment of the paper to insure smooth and proper feed through the apparatus, but makes it possible to adjust the various sheets 60 transversely to cause their edges to meet properly when they are brought together. The adjustments of the rollers 46 and 44 relative to the steel roller 42 will be readily seen to afford close control 65 of the pressures on the laminations throughout their width. Thus wide sheets may be readily laminated together with uniform thickness throughout their widths. Other adjustments to insure uniformity across the width of wide webs are afforded by the mountings of the equalizers.

70 The proper control of the speed of the chilling rolls 74 and 76 is also desirable to secure a satisfactory product. Fine control of the speeds of these rolls is effected through the use of the cone pulleys over which the belt 260 runs.

One of the most important features of the machine is the treatment of all sheets to substantially the same conditions of temperature and coating. By reason of this there are no differential conditions imposed on the sheet which tend to produce curl and stresses which might promote separation of the plies. There is thus caused to result a non-curling product with a stronger bond between the sheets.

It will be clear that various modifications of the invention may be made within the scope of the appended claims.

What I claim and desire to protect by Letters Patent is:

1. An apparatus for laminating webs of paper or the like comprising a metal roller, means for driving said metal roller, and a resilient roller arranged to press together and against said metal roller a plurality of said webs having adhesive between them, said resilient roller being rotatable solely under the action of said webs and during its rotation being locally compressed, thereby constituting a load upon said driving means applied through said webs.

2. An apparatus for laminating webs of paper or the like comprising a metal roller, means for driving said metal roller, and a resilient roller arranged to press together and against said metal roller a plurality of said webs having adhesive between them, the ends of the axis of said resilient roller being independently adjustable towards and from the axis of said metal roller.

3. An apparatus for laminating webs of paper or the like comprising a metal roller, means for driving said metal roller, and a plurality of resilient rollers arranged to press together and against said metal roller a plurality of said webs having adhesive between them, said resilient rollers being rotatable solely under the action of said webs and during their rotation being locally compressed, thereby constituting loads upon said driving means applied through said webs.

4. An apparatus for laminating webs of paper or the like comprising a metal roller, means for driving said metal roller, and a plurality of resilient rollers arranged to press together and against said metal roller a plurality of said webs having adhesive between them, the ends of the axis of each of said resilient rollers being independently adjustable towards and from the axis of said metal roller.

5. An apparatus for laminating webs of paper or the like comprising a plurality of rollers arranged to press together a plurality of said webs having adhesive between them, means for applying adhesive to the webs comprising a roller, and an equalizer rod, and means for adjusting said

equalizer rod about the axis of said adhesive applying roller at a substantially constant distance from said axis.

6. An apparatus for laminating webs of paper or the like comprising a plurality of rollers arranged to press together a plurality of said webs having adhesive between them, means for applying adhesive to the webs, and means for adjusting supply rolls of web materials axially with respect to each other, the last named means comprising braking means for the supply rolls, means for adjusting the tensions imparted by the braking means, and means for adjusting the braking means axially to adjust said supply rolls therewith.

7. An apparatus for laminating webs of paper or the like comprising a plurality of rollers arranged to press together a plurality of said webs having adhesive between them, means for applying adhesive to the webs, and means for adjusting at least one supply roll of web material axially with respect to the other, the last named means comprising a grooved member secured to the supply roll, means engaging within the groove of said member, and means for moving the last named means, and with it the supply roll, axially.

8. An apparatus for laminating webs of paper or the like comprising a plurality of rollers arranged to press together a plurality of said webs having adhesive between them, means for applying adhesive to the webs comprising a roller, an equalizer rod, a massive metallic carrier for the equalizer rod provided with a socket in which said rod rests and rotates, and means for heating said carrier, and through it by conduction from said socket, said equalizer rod.

9. An apparatus for laminating webs of paper or the like comprising a plurality of rollers arranged to press together a plurality of said webs having adhesive between them, means for applying adhesive to the webs, and means for abrading, before it reaches said adhesive applying means, the side to which adhesive is to be applied of at least one of said webs.

10. An apparatus for laminating webs of paper or the like comprising a plurality of rollers arranged to press together a plurality of said webs having adhesive between them, means for applying adhesive to the webs comprising a roller, and means for adjusting the path of approach of at least one of said webs to an adhesive applying roller, said means comprising a plurality of rollers adjustable as a unit in a direction transverse to the path of approach of the web to the adhesive applying roller.

JOHN N. TUTTLE.
